UNITED STATES PATENT OFFICE.

BEAUMONT T. STREET, OF SPRINGFIELD, MISSOURI.

HEATING DEVICE.

Application filed May 12, 1922. Serial No. 560,419.

To all whom it may concern:

Be it known that I, BEAUMONT T. STREET, a citizen of the United States, residing at Springfield, in the county of Greene and 5 State of Missouri, have invented certain new and useful Improvements in Heating Devices, of which the following is a specification.

This invention relates to heating devices, 10 and more particularly to control means for furnaces and other heating appliances.

An object of the invention is the provision of a simplified draft control by means of which perfect combustion of the fuel is 15 obtained.

A further object is the provision of a check draft whereby economy of fuel is obtained.

A further object is the provision of a 20 draft control which will provide proper supply of air for any regulated condition.

In the accompanying drawings, I have shown one embodiment of the invention. In this showing:

25 Figure 1 is a side elevation, parts being shown in section,

Figure 2 is a detail sectional view on line 2-2 of Figure 3,

30 Figure 3 is a horizontal sectional view on line 3-3 of Figure 1, and,

Figure 4 is a perspective view of the attachment detached.

Referring to the drawings, the reference 35 numeral 1 designates a furnace or heater of any type, such as a hot air furnace, the boiler of a hot air or steam heating system, or an ordinary heating stove. The furnace is provided with a fire door 2, and an ash pit door 3 opening into an ash pit 4 (see Figure 40 3). A stack 5 communicates with the top of the fire box 6. The furnace or boiler may be surrounded by a suitable casing 7 of sheet metal or other suitable material.

The attachment forming the subject matter 45 of the present invention consists of an air pipe 8, arranged adjacent the furnace and extending from the floor or foundation to a point above the top of the furnace. The upper end of this pipe is connected by an elbow 9 to a horizontal portion 10, communicating with the stack. The lower end of this pipe communicates with a throat 11, having an inlet opening 12. A draft regulator 13 is arranged in the throat and is adapted to 50 control communication between the inlet 12

and the pipe 8. This draft regulator is mounted on a hinge or pivot 14, and is controlled by a lever 15, arranged on the exterior. Beyond the valve, the throat branches into a pair of substantially semi-circular 60 conduits 15 which extend around the furnace (see Figure 1) and communicate with the ash pit through openings 16.

In operation the valve or damper 13 is adapted to be arranged in the position 65 shown in full lines in Figure 2 of the drawings, to cut off the draft from the furnace. Air entering opening 12 then passes through pipes 8 and 10 to the stack 5. If the valve is swung to its extreme other position, closing the lower end of the pipe 8, the furnace 70 draft is then open and the entire supply of air passes from the throat 11 through conduits 15 to the ash pit, thence through the grate to the fire box. The draft may be set 75 at any intermediate point, as indicated in dotted lines in Figure 2. The capacity of pipe 8 is equal to the capacity of the smoke pipe, whereby the same volume of air passes through each of these pipes and proper combustion is thus obtained.

It is to be understood that the form of my invention herewith shown and described is to be taken as a preferred example of the same, and that various changes in the shape, 85 size, and arrangement of parts may be resorted to without departing from the spirit of the invention or the scope of the subjoined claims.

Having thus described my invention, I 90 claim:

1. A draft attachment for furnaces comprising a pipe arranged adjacent the furnace and communicating with the stack of the furnace at its upper end, a throat communicating with the lower end of said pipe, said throat being provided with an inlet opening, a conduit extending from said throat to a point where air is taken into the furnace to feed the fire, and a valve arranged in said throat and adapted to afford communication at all times with either said pipe or said conduit or both and being adapted to entirely close either said pipe or said conduit, the capacity of said pipe being 95 substantially equal to the capacity of the stack of the furnace.

2. A draft attachment for furnaces comprising a pipe arranged adjacent the furnace and communicating with the stack of the 100

furnace at its upper end, a throat communicating with the lower end of said pipe, said throat being provided with an inlet opening, a substantially semi-circular conduit surrounding the furnace and connecting said throat to the furnace beneath the grate, and a valve arranged in said throat and adapted to afford communication at all times with either said pipe or said conduit or both and being adapted to entirely close either said pipe or said conduit, the capacity of said pipe being substantially equal to the capacity of the stack of the furnace.

3. A draft attachment for furnaces comprising a pipe arranged adjacent a furnace and communicating with the stack of the furnace at its upper end, a throat communicating with the lower end of said pipe, said throat being provided with an inlet opening,

a pair of substantially semi-circular conduits surrounding the furnace and connecting said throat to the furnace beneath the grate, and a valve pivotally mounted in said throat and adapted to afford communication at all times with either said pipe or said conduits or both and being adapted to entirely close either said pipe or said conduits, said valve being provided with an operating handle, the capacity of said pipe being substantially equal to the capacity of the stack of the furnace.

In testimony whereof I affix my signature in presence of two witnesses.

BEAUMONT T. STREET.
